UNITED STATES PATENT OFFICE.

WILLIAM NICHOLS BEARDSLEY, OF BRIDGEPORT, CONNECTICUT, ASSIGNOR
TO MARCELLUS HARTLEY AND MALCOLM GRAHAM, OF NEW YORK, N. Y.

DESIGN FOR A WALL-SUPPORT FOR BICYCLES.

SPECIFICATION forming part of Design No. 25,282, dated March 24, 1896.

Application filed February 12, 1896. Serial No. 579,084. Term of patent 3½ years.

To all whom it may concern:

Be it known that I, WILLIAM NICHOLS BEARDSLEY, a citizen of the United States, residing at Bridgeport, in the county of Fairfield and State of Connecticut, have invented and produced a new and original Design for Bicycle Wall-Supports; and I do declare the following to be a full, clear, and exact description of the same, reference being had to the accompanying drawing, forming a part thereof.

The leading feature of my design is the base-plate A, adapted to rest against a vertical wall, combined with the wire bicycle supporting-arms B B, whose free ends are anchored in the bosses C C, projecting from the front surface of the supporting-plate, combined with the end connection B', which firmly unites said arms to form a rigid support or loop for a bicycle-wheel when forced between such arms.

Immediately in front of the plate A the arms B B assume an upward curve at the point B² B². These curves blend into straight

upward-projecting lines to a point about midway of said arms, where the single coil D is formed in the body of said arms, thence upward to the point B', thus completing the loop.

The holes E E are formed in the plate A for supporting screws.

As before mentioned, the leading feature of my design is the broad supporting-plate, with the loop-arms projecting therefrom, substantially as shown. The form of the plate may vary as well as the several curves of the arms without departing from my general design, except the first curves B², which should have an upward turn.

What I claim is—

The design for a bicycle wall-support, substantially as herein shown and described.

In testimony whereof I affix my signature in presence of two witnesses.

WILLIAM NICHOLS BEARDSLEY.
